(57) CLAIM

The ornamental design for a chair, as shown and described.

DESCRIPTION

FIG. 1 is a front view of a chair constructed in accordance with the present invention;

FIG. 2 is a top view of the chair of FIG. 1;

FIG. 3 is a back view of the chair of FIG. 1;

FIG. 4 is a bottom view of the chair of FIG. 1; and,

FIG. 5 is a perspective view of the chair of FIG. 1.

The broken line showing of the chair is for the purpose of illustrating portions of the “article” and forms no part of the claimed design.

1 Claim, 5 Drawing Sheets
